UNITED STATES PATENT OFFICE.

WILLIAM R. JONES, OF BRADDOCK, PENNSYLVANIA.

FEEDING APPLIANCE FOR ROLLING-MILLS.

SPECIFICATION forming part of Letters Patent No. 340,917, dated April 27, 1886.

Application filed July 20, 1885. Serial No. 172,091. (No model.)

To all whom it may concern:

Be it known that I, WILLIAM R. JONES, of 5 Braddock, in the county of Allegheny and State of Pennsylvania, have invented a new and useful Improvement in Feeding Appliances of Rolling-Mills; and I do hereby declare the following to be a full, clear, and exact description thereof.

My improvements in the feed appliances of 10 rolling-mills are especially applicable to rail and similar mills, in which a large and heavy bloom is drawn out into a long rail, beam, or similar article. Such articles are heavy and unwieldy, and various devices have been used 15 for feeding them to the rolls, for shifting them from one pass to another, for transferring them from one set of rolls to another, and for turning the piece.

My improvements relate to such appliances, and my object is to make the operation 20 of such a mill as nearly automatic as possible, whereby time and labor are economized, the output increased, and repairs lessened.

To enable others skilled in the art to make 25 and use my invention, I will now describe it by reference to the accompanying three sheets of drawings, in which—

Figure 1 is a plan view of a train of rolls 30 for making railroad-rails provided with my improvements. Fig. 2 is a section on the line A B of Fig. 1. Fig. 3 is a section on the line C D of Fig. 1. Fig. 4 is a detail.

Like figures of reference indicate like parts in each.

The train is made of three different sets of 35 rolls, 1, 2, and 3, each being three high, so as to afford return-passes without necessitating reversing the rolls. The roughing-rolls 1 are provided with rising and falling feed-tables 40 4, 5, one at the front and the other at the rear side. These tables are composed of rollers 6, journaled in frames 7, and geared together at 8. One of the geared roller-shafts is provided with a friction-wheel, 9, at one or both 45 ends.

Extending transversely under the table 4 is a power-shaft, 10, which is provided with 50 friction gear-wheels 11, arranged directly under the wheels 9, so that when the table 4 falls into position to feed an ingot or bloom to the lower passes of the roughing-rolls 1, the fri-

tion-wheels 9 shall come into contact with the wheels 11 and be turned thereby, and cause the rollers 6 of table 4 to turn in a feeding direction. The rollers 6 of table 5 are driven 55 in like manner, except that being designed for such use with the upper pass they are driven when the table is raised and not when it is depressed. In this case the driving-wheels 12 are mounted on a shaft, 13, above 60 the table 5. Then, when the table is raised into position to feed to the upper pass, its friction-wheels 9 come in contact with and are driven by the friction-wheels 12. The shaft 13 is driven from the power-shaft 14 by means 65 of the vertical shaft and pinions 15.

The tables 4 and 5 may be raised and lowered by any suitable means, many of which are well known. I show in the drawings the application of a hydraulic cylinder for the 70 purpose. (See Fig. 2.) Here the cylinder is shown at 16, and the tables 4 and 5 are supported by pitmen 17, which are connected to cranks 18. The crank-shafts 19 are operated by a rod, 20, connected with the ram or piston 21. The tables are guided in their vertical movements by the sleeves 22, moving on the vertical guide-rods 23, attached to the housing 24.

Journalized in the housing at the delivery 80 side of the upper and lower passes are driven delivery-rollers 25—one at each level. The one at the front side is driven by a belt, 26, extending from a pulley, 27, on the power-shaft 10, to a pulley, 28, on the end of the 85 shaft of the front roller, 25, and the one at the rear side is driven by a belt, 29, extending from a pulley, 30, on the shaft 13 to a pulley, 31, on the shaft of the rear roller, 25. The purpose of this construction is to facilitate the 90 discharge of the piece from the rolls.

It is apparent from the foregoing description that the rollers 6 of the table 4 are driven by power when the table is down and acting as a feed-table, and that when it is up and 95 acting as a receiving-table the rollers are turned, if at all, only by the friction of the bloom as it comes from the rolls. The rollers 6 of the table 5, on the other hand, are driven by power only when such table is up and in 100 position to feed the bloom to the upper passes, and when the table is down in a position to re-

receive the bloom from the lower passes, as shown in Fig. 2, the rollers are turned by the friction of the bloom alone. The driven rollers 25 insure the proper delivery of the bloom 5 from the rolls to the table, and obviate all danger of its stopping so near the rolls or guides as to interfere with its proper transfer by the tables from one pass to another.

Secured to the floor in front of the rolls 10 and projecting up between the rolls 6 of the table 4 are two rows of inclined guides, 32 and 33, the purpose of which is to shift the bloom from one of the upper passes over to the next lower pass to the right, (or left, as the case may be,) and to turn it while being shifted.

By reference to Fig. 3 it will be noticed that the surface of the rollers 6, when the table 4 is in its upper position, is above the upper ends 20 of the guides 32 33. The bloom having gone through pass *a* and returned through pass *b* to the table 4, the latter is caused to fall. As it does so the bloom encounters the inclined upper sides of the guides 32, and is shifted thereby 25 over on the table, until when the latter reaches its lower position it lies in front of the pass *c*. At the same time the bloom is tipped by the inclines and turns over as it descends to place. When the table 4 reaches its lower position, 30 the friction-wheels 9 encounter the friction-wheels 11, and are set in motion, starting the rollers 9, which drive the bloom into the pass *c*. The operation of the guides 33 is the same, turning the bloom between the passes *f* and *g*. I have shown two of the guides 32 and three 35 of 33. The reason for this is that the bloom has been elongated when it reaches the guides 33, and requires an additional one to direct its outer end.

40 The rolls 2 are provided with stationary feed-tables 34 and 35, consisting of suitable frames in which are journaled driven feed-rollers 36, having intermediate platforms, 37. The rollers of the table 34 are driven toward the rolls 2 by shaft 38, connected therewith by bevel-gearing, said shaft being driven by a second shaft, 39, through the medium of friction gear-wheels 40. The shaft 39 is driven by the power-shaft 10 through the medium of 45 bevel-gearing 41. The rollers 36 of the table 35 are driven toward the rolls 2 by a shaft, 42, connected therewith by bevel-gearing. It receives power from the shaft of one of the rollers 36, (in this case the outer one,) which is 50 connected by gearing 43 with, and is driven by, a shaft, 44. The other end of the shaft 44 is mounted in a sliding bearing, 45, so as to be capable of a slight lateral movement, and is provided with a friction gear-wheel, 46, placed 55 between two geared friction-wheels, 47, one of which is mounted on a shaft, 48. The shaft 48 is driven by the power-shaft 14, with which it is connected by gearing 49. The shaft 39 is also mounted on sliding bearings 50, so that 60 the friction-wheels 40 may be thrown into and out of contact by means of a lever connected to the rotating rod 51, which in turn is suitably 65

connected with the sliding bearings 50. The purpose of this construction is to disconnect the feed-rollers 36 of the table 34 whenever it is desired to prevent the bloom thereon from being driven into the pass, as is occasionally the case. The friction-wheel 46 is thrown into gear with either of the wheels 47 at pleasure by means of a lever, 52, connected with the sliding bearings 45 by a system of rods and levers, 53, for the purpose of causing the feed-rollers 36 of the table 35 to be driven in either direction, as may be desired.

Extending along the inner side of the feed-table 4 is a rock-shaft, 54, which is provided with two or more radial arms or levers, 55, and hinged at or to the adjacent side of the frame of the table 34, at 56, are a like number of slideways or bars, 57, which, near their outer ends, rest on the levers 55. The inner ends of the bars 57 terminate between or at the side of the rollers 36 of the table 34, and the upper or outer ends, which are beveled to receive the bloom as it comes from the last pass, *h*, of the roughing-rolls 1, terminate between the rollers 6 of the table 4 when the latter is in a raised position. On the floor under the rock-shaft 54 is another rock-shaft, 58, which is provided on one side with an arm or lever, 59, which bears against a friction-roller, 60, on the under side of the frame 7 of the table 4, and projecting from the other side of the rock-shaft 58 is a counterweighted arm, 61, which holds the arm 59 in contact with the friction-roller 60 as the table 4 rises and falls. The arm 59 is pivotally connected with an arm, 62, which projects from the lower side of the rock-shaft 54 by a link, 63.

The operation of this construction is illustrated in Fig. 3, and is as follows, viz: When the table 4 is in a raised position, the beveled ends of the bars 57 lie between the rollers 6 in front of the pass *h*, as shown by dotted lines, so that the bloom from the latter shall lie on the table directly above them. Then, when the table 4 falls, it depresses the arm 59, which by means of the link 63 and arm 62 turns the rock-shaft 54, causing the lever 55 to raise the slideways 57. The latter raises the bloom 64 up off the table 4, when its gravity will cause it to slide down the ways 57 to the table 34, where it is stopped by the stop 65 in front of the first pass, *i*, of the rolls 2. The bloom when it leaves the pass *h* is of *T* form, and it 70 slides down the ways 57 stem foremost, so that when its stem encounters the stop 65 it is turned to an upright position, and is therefore in the proper position to be driven by the rollers 36 into the pass *i* without turning or further manipulation. The rail-bloom after going through the pass *i* runs out on the table 35, and then its rear end is raised by means of a lever-hook or otherwise to the pass *k*, through which it is driven. As its latter end leaves the 75 pass *k* it falls to the table 34, but in its descent it encounters an inclined guide, 66, which shunts it sidewise, so that it falls on the table directly in front of the pass *l*. The feed-rolls

ers 36, turning in the direction of the rolls, then carry the bloom directly into said pass.

If desired, a similar guideway may be arranged between the passes *m* and *n*. The bloom having gone through pass *n* and run out on the table 35, the rollers 36 of the latter are stopped by throwing the friction-wheel 46 out of contact with the wheels 47. At the rear end of the table 35 is a track, 67, which extends also over the rear feed-table of the finishing-rolls 3. Mounted on this track is a carriage or pusher, 68, which is operated by a chain or rope, 69. The rope 69 is mounted on sheaves 70, placed at the ends of the track, and is actuated by a drum, 71, around which it passes one or more times. The drum is mounted on a shaft journaled in a sliding bearing, 72, and is provided with a friction-wheel, 73, at the other end, which wheel is situated between two friction gear-wheels, 74, and is capable of being thrown into contact with either, or out of contact with both. The bearing is moved by a lever, 75, with which it is connected by a rod, 76. By throwing the wheel 73 in contact with one of the wheels 74, the carrier 68 is caused to move in one direction, and by throwing it in contact with the other the carrier is caused to move in the opposite direction. When the rail-bloom leaves the pass *n* it is very much elongated, and its end extends past the carrier 68, the latter being in its retracted position, as shown in Fig. 1.

The rolls 3 have a feed-table, 75^a, on the front side, which is similar to the table 34 as to construction and power devices, but owing to the greater length of the rail-bloom it is provided at the outer end with one or more friction-rollers, 76^a, and intermediate platforms. The rear feeding-table, 77, is merely 40 the elongation of the transfer table or bed, which carries the rail to the saws. In this table 78^a are the friction-rollers, and 79 are the adjacent driven rollers of the transfer-table leading to the saws. The latter are driven by 45 a shaft, 80, which is connected to the axles of the rollers by bevel gearing, and the shaft is driven by a belt, 81, leading from a suitable power-shaft.

Journalized in the table 77 are two shafts, 82, 50 which are driven by belts 83 and 84 from the power shaft 14, and on their inner ends directly in front of the first pass of the finishing-rolls 3, are tapered feed-rollers 85, having collars on their inner ends, to prevent the rail from 55 being pushed clear over them.

Extending from a point near the outer end of the table 35 to the adjacent side of the table 77 is a slideway or bar, 86, which aids in supporting the rail as it is transferred from the 60 table 35 to the feed-rollers 85.

In transferring the rail-bloom from the table 35 to the feed rollers 85, the end next to the rolls is supported and guided by the workman by means of a suspended hook-lever—such as 65 is commonly used for moving blooms in rolling-mills—and the bloom is pushed over by the carrier 68, which is set in motion, as described,

for that purpose, until it is placed on the rollers 85 against the collars of the same. The rollers then drive the bloom into the first pass 70 of the rolls 3. The driven rollers of the table 75 return it to the rolls, which finally deliver it on the table 77, whence it is carried to the saws by the rollers 79.

The rolls 3 may be provided with an inclined guide, similar to the guide 66 on the rolls 2, and for the same purpose, if desired. The shafts 10 and 14 are driven by counter-shafts 87, extending from the roll-shaft 88. If desired, a second carrier, 68, may be arranged 80 between the tables 35 and 77, and the rail-bloom be transferred by the carriers without manual labor.

The pitmen 17 and their cranks 18 are made of different lengths, so that when the tables 4 85 and 5 are in receiving positions they shall turn on their pivots and incline from the rolls 1, so as to facilitate the delivery of the bloom.

It is evident that one of the rising and falling tables (4 or 5) may be used with advantage 90 without the other, in which case the bloom may be handled on the opposite side of the rolls in any other desired way; also, that the table may be used for some kinds of work with but one driven feed-roller, in which case the 95 other rollers would not be geared thereto, but would turn by the friction of the bloom; also, that the feed-tables may have separate elevating devices; also, the pivoted incline slideways may be used without feed-tables; also, 100 that the rising and falling feed-tables may be raised by the direct action of hydraulic or steam pistons, and the tipping motion communicated to them therewith. These changes will be obvious to the skilled mechanic. 105 The free ends of the slideways 57 project over the adjacent side of the table 4, and in the absence of the raising mechanism, of which shaft 54 is the center, the slideways, arranged as shown, would rise and fall with the table 4. 110 They can therefore be used without other means than the said table for raising and lowering them, and, as they constitute a valuable and useful feature when so used, they are claimed in connection with tables alone, as 115 well as in connection with other raising mechanism.

What I claim as my invention, and desire to secure by Letters Patent, is—

1. The combination, in a rolling-mill, of a 120 rising and falling feed-table having geared feeding-rollers, with a fixed driving mechanism arranged at the feed side of the pass, whereby the feeding-rollers are driven toward the pass when the table is brought to a feed 125 position, substantially as and for the purpose described.

2. The combination, in a rolling-mill, of a 130 rising and falling feed-table having a feed-roller provided with a friction gear-wheel, with a driving friction-wheel occupying a fixed position relatively to the table in a different horizontal plane, whereby the friction-wheel on the table shall come automatically

in contact therewith when the table comes to a feeding position, substantially as and for the purposes described.

3. The combination, with a three-high mill, of simultaneously rising and falling feed-tables arranged on opposite sides of the rolls and provided with feed-rollers, and fixed mechanism placed below the table on one side and above the table on the other side, whereby by the feed-rollers of the tables shall come automatically into connection with the driving mechanism when they assume position on the feeding side of a pass, and shall be automatically disconnected when they move away from such position, substantially as and for the purposes described.

4. The combination, in a three-high mill, of a rising and falling feed-table having geared feeding-rollers and a friction-wheel connected with such rollers, with a driving friction-wheel occupying a fixed position relatively to the table, with which the friction-wheel on the table in another horizontal plane shall come automatically into driving contact when the table is raised or lowered to a feeding position, substantially as and for the purposes described.

5. The combination, in a rolling-mill, of a rising and falling feed-table having geared feed-rollers, with a fixed driving mechanism, which is in driving connection with the feed-rollers when the table is in a feeding position, and out of connection when it is in a receiving position, and a driven roller arranged on the delivery side of the rolls between the rolls and the receiving-table, substantially as and for the purposes described.

6. The combination of a set of rolls having a rising and falling feed-table, with a second set of rolls having a feed-table, and inclined slideways pivoted at the second feed-table, and having their free ends terminating at the first for the purpose of transferring the piece from the first set of rolls to the second, substantially as and for the purposes described.

7. The combination, in a rolling-mill, of a set of rolls having a rising and falling feed-table, pivoted inclined slideways having their free ends terminating at an upper pass of the rolls, and supporting arms sustaining the free ends of the slideways and connected with the table, and mechanism for operating said arms, whereby the free ends of the slideways shall fall below the said upper pass at the rise of the table, and shall rise and lift the bloom from the table as the latter falls, substantially as and for the purposes described.

8. The combination, in a rolling-mill, of a

set of rolls having a rising and falling feed-table, pivoted inclined slideways having their free ends terminating at an upper pass of the 60 rolls, a rock-shaft provided with oscillating arms which sustain the slideways, and levers connected to said rock-shaft, actuated by the table, whereby the fall of the table shall cause the slideways to rise and lift the bloom from 65 the table, substantially as and for the purposes described.

9. The combination, in a three-high mill, of a rising and falling feed-table having feed-rollers, with stationary guides projecting up 70 between the feed-rollers, having inclined surfaces between the upper and lower passes to shift the bloom laterally and turn it radially as the table descends, and a fixed driving mechanism arranged below the table, which 75 comes into automatic connection with the feed-rollers when the table reaches its lower position and the bloom is shifted and turned, so that the bloom may at once be automatically driven by the feed-rollers of the table into the 80 next pass without turning or other manipulation, substantially as and for the purposes described.

10. The combination, in a rolling-mill, of two sets of rolls, with inclined slideways pivoted 85 near the lower pass of one set of rolls, and extending to the upper pass of the first set of rolls, and mechanism for supporting the free ends of the slideways and raising them, for the purpose of receiving and raising the bloom from 90 the first set of rolls and transferring it by gravity to the other rolls, substantially as and for the purposes described.

11. The combination, in a rolling-mill, of two sets of rolls, each provided with feed-tables, with a carrier for transferring the bloom laterally from one feed-table to the other, substantially as and for the purposes described.

12. The combination, in a rolling-mill, of two sets of rolls, one set having a feed-table 95 and the other set having driven flanged feed-rollers arranged in front of its first pass, with transfer-bars extending from the feed-table to the feed-rollers, so that the bloom may be shifted laterally thereon from the feed-table to the 105 feed-rollers, substantially as and for the purposes described.

In testimony whereof I have hereunto set my hand this 18th day of July, A. D. 1885.

WILLIAM R. JONES.
